MOISTENING DEVICES

Samuel Kirschenbaum, Brooklyn, N. Y.

Application June 2, 1955, Serial No. 512,743

3 Claims. (Cl. 141—198)

This invention relates generally to the field of moistening devices, and more particularly to an improved form of such device particularly adapted for use in fueling pyrophoric lighters of a type used by smokers, in which the fuel is carried within a casing having absorbent cotton stuffed therein to prevent the fuel from running out.

It is among the principal objects of the present invention to provide a device of the class described in which the flow of fuel from a container of the same to the lighter is under accurate control so that it is possible to provide all of the fuel which the absorbent cotton will hold, while yet preventing the excess flow of fuel such that it will run from the lighter to soil the hands of the users and present a possible fire hazard.

Another object of the invention lies in the provision of a moistening device possessed of the above advantages, in which the cost of fabrication may be of a very low order, thereby permitting consequent wide sale, distribution and use.

Another object of the invention lies in the provision of integral container stopper means adapted to seal a container of fuel when the device is not in use.

Still another object of the invention lies in the provision of a moistening device in which accuracy of flow control to a degree hitherto impossible is obtained by those possessed of only ordinary skill.

These objects, as well as other incidental ends and advantages, will become more clearly apparent during the course of the following disclosure, and be pointed out in the appended claims.

Before entering into a detailed consideration of the invention, a brief discussion of the theory involved in the operation of the same will assist in the comprehension of the structural aspects of the invention.

The field of organized flow of liquids from containers by natural forces takes in all liquid dispensing devices which, when brought into a pouring position, are characterized by an inner space completely isolated from the outside atmosphere. In all such dispensers, a partial vacuum develops and the flow of liquid from them takes place under the influence of normal pressure of the outside atmosphere, and a sub-normal pressure in the isolated air space. They are designated in this application as primary dispensers, and are divided into two groups to be known as primary first stage and primary second stage.

In my Patent No. 2,576,403, granted November 27, 1951, for drop device, the action described is that of a primary first stage dispenser which gives up limited amounts of liquid by intermittently turning the dispenser to a pouring position. There is no continuous flow and the volume of liquid dispensed with each such action is determined by the relationship of the weight of the liquid and the volume of air within the container.

In my earlier Patent No. 2,411,435, the action described is that of a secondary stage dispenser in which the action is continuous as long as it is kept in a pouring position.

In accordance with the present invention, the complete dispenser, including a bottle or other container for fuel and the device, is held in an upright position, and the

2

lighter minus its screw cap or other covering device is brought down over it such that the spout is in full contact with the absorbent material disposed therein. Following this, both lighter and dispenser are turned

5 downwardly with the original contact maintained throughout, and with the weight of the dispenser providing sufficient pressure for that purpose. At this point, there may be observed a stream of bubbles entering the container. When these bubbles stop completely, the 10 lighter and dispenser are brought back together into an upright position. The lighter is then removed and ready for use.

The self-limiting action of the dispenser, which prevents the lighter filling to excess, takes place in the following 15 manner. The act of turning the dispenser downward frees a small amount of liquid which is picked up by the absorbent material, which then continues to pull liquid from the container. The partial vacuum deepens until air breaks through a venting means in the wall of 20 the spout.

A cut without displacing any material is the smallest 25 opening that can be provided for the passage of fluids, liquids or gases, and constitutes under any given set of circumstances the greatest degree of resistance to their passage. It requires a differential in pressure above a certain point to force any fluid through the cut. The resistance point therefore remains constant.

As the absorbing medium soaks up fluid, its pulling 30 power decreases, and when it drops to the point where it equals the resistance the action stops.

The degree of wetness of any absorbing medium is 35 determined by the degree of resistance that is established. In cigarette lighters the venting action is stopped at a point just below the point of maximum mass tension of its absorbent material. If carried beyond that point dripping takes place and excess liquid spreads to the outside of the lighter with consequent discomfort to the user.

With the foregoing discussion in mind, reference may 40 now be made to the accompanying drawing, in which similar reference characters have been employed to designate corresponding parts throughout the several views.

Figure 1 is a view in perspective of a first embodiment of the invention.

Figure 2 is a vertical central sectional view of the 45 embodiment.

Figure 3 is a view in elevation, partially broken away to show detail, and showing the position of various parts during a filling operation.

Figure 4 is a plan view of the embodiment.

Figure 5 is a vertical sectional view as seen from the plane 5—5 on Figure 4.

Figure 6 is a view in elevation, corresponding to that seen on Figure 3, but showing a second embodiment of the invention.

Figure 7 is a plan view of the second embodiment.

Figure 8 is a vertical sectional view as seen from the plane 8—8 on Figure 7.

Figure 9 is a sectional view of the venting means employed in the second embodiment.

Figure 10 is a sectional view of the venting means employed in an alternate form of the first and second embodiment.

The first embodiment of the invention, generally indicated by reference character 10, comprises broadly: a liquid conducting element 11, venting means 12, and a stopper element 13, the device being shown on Figure 1 with the stopper element 13 in position within a neck portion 14 of a conventional glass bottle of fuel. On Figure 3 there is shown a conventional pyrophoric lighter 16 having absorbent cotton means 17 for retaining fuel therein.

The liquid conducting element 11 is preferably formed completely from an integral piece of polyethylene or similar synthetic resinous material possessing desired degree of resiliency and flexibility. It includes a neck engaging member 20, a collar member 21 and a nozzle member 22 having a lighter engaging terminal 23 thereon. A centrally disposed duct 24 extends through the members 20-23, the inner terminal 25 being disposed within the container of fuel 15 when the device is in use. As may be seen on Figures 1 and 5, the duct 24 is generally 10 tapered in a direction toward the terminal 23 and is provided with a plurality of small grooves 24' which prevent bubbles of air in the duct from interfering with the flow of fuel. The venting means 12 is in the form of an elongated slit 30 which is cut from the outer surface 15 31 of the nozzle 22 to the inner surface 32 thereof, and which extends from the end surface 33 to the collar member 21, as best seen on Figures 1 and 3. The cut is made with a sharp instrument, in such a manner that the side surfaces 35 and 36 forming the cut are normally 20 resiliently urged against each other by the resilient characteristics of the material of which the device is made. As the thickness between the outer surface 31 and inner surface 32 at the slit formed by the mutually contacting 25 surfaces 35 and 36 is appreciable, an effective seal requiring a substantial pressure differential for the passage of air therethrough is obtained. On Figure 5, the surfaces 35 and 36 are shown in slightly spaced relationship for purposes of clarity, but it is to be understood that the space between the same is exaggerated, and normally the space between the same is practically immeasurable. Thus, during operation, only very small amounts of air are admitted provided the surface 23 is kept in contact with the cotton 17, these amounts occurring at regular intervals at such time as the pressure differential between the inside of the container 15 and the ambient air is sufficiently great to force air through the slit 30.

The stopper element 13 is preferably formed of solid material, as shown on Figure 2, and may be alternately positioned with the neck engaging member 20 within the opening in the container 15, as shown on Figure 3. If desired, the stopper element 13 may be eliminated, and separate stopper means (not shown) may be employed.

Turning now to the second embodiment of the invention as shown on Figures 6, 7, 8 and 9, parts corresponding to those of the first embodiment have been designated by similar reference characters to avoid needless repetition.

The second embodiment of the invention differs from the first embodiment in the construction of the venting means, wherein the slit 30 is substituted by a small hole 41, the nozzle member being provided with a knit or woven sock 42 having a side portion 43 adapted to cover the hole 41, and an end portion 44 adapted to lie across the end of the duct 24.

During use, the first stage liquid flowing from the container completely saturates the sock 42, to a degree sufficient to seal the hole 41. When the device reaches the second stage of operation, the capillary action of the cotton 17 will draw liquid from the sock, to a degree sufficient to permit a small amount of air to flow through the hole 41, thus permitting additional liquid to flow through the duct. When a saturation point is reached, excess liquid again saturates the sock, and closes the hole 41 to prevent further flow.

Turning now to the alternate form of the first or second embodiment, this differs from the principal form in the provision of a duct 24a of rectangular cross section, further supplementing the action of the groove 24'.

It may thus be seen that I have invented novel and highly useful improvements in moistening devices particularly adapted for use in filling pyrophoric lighters and similar devices, in which the liquid flowing from the device is accurately controlled and ceases upon reaching a point wherein the lighter is completely saturated with

fuel. The device may be formed entirely from a single injection molding of a type well known in the art, thus keeping the cost of manufacturing the same at a very low figure. As there are no moving parts in the device, there are no points of potential failure which might cause faulty operation with continued usage. No unusual skills are needed in the operation of the device, nor can the device get out of adjustment with continued usage.

I wish it to be understood that I do not consider the invention limited to the exact details of structure shown and set forth in this specification, for obvious modifications will occur to those skilled in the art to which the present invention relates.

I claim:

1. A moistening device for use in conjunction with a container of fuel for filling a pyrophoric lighter and similar devices having a fuel reservoir containing absorbent material comprising: an elongated tube formed substantially entirely of a resilient material and having a principal axis and first and second end portions, means on said first end portion for engaging an opening in said container of fuel in substantially hermetically sealed relation, said tube having an axially disposed channel therein extending from said first end portion to said second end portion and a slit extending from said second end portion in a direction toward said first end portion, said slit extending completely through said tube from the outer surface thereof to the surface of said channel and having first and second opposed side surfaces which are maintained in contact forming a substantially sealed relationship by the normal resiliency of the material from which the device is formed; said second end portion being positionable in contact with said absorbent material to permit fuel to flow under capillary action to a point where said absorbent material is completely saturated during which process said slit permits the passage of a sufficient quantity of air therethrough to substantially equalize the pressure differential between the interior of said fuel container and the ambient atmosphere, the resilient contact of said side surfaces preventing further flow of air to the interior of said fuel container upon termination of capillary action with the complete saturation of said absorbent material.

2. A moistening device for use in conjunction with a container of fuel for filling a pyrophoric lighter or similar device having a fuel reservoir containing absorbent material, comprising: a liquid conducting element providing a channel through which fuel may flow from said container; and venting means in the form of a small opening extending through said liquid conducting element adjacent one end thereof, providing communication with said channel and the ambient atmosphere, a textile sock member covering said opening and extending into the path of liquid flowing through said liquid conducting element, whereby said sock member will become moistened during the course of filling said fuel reservoir, and absorb fuel by capillary action when the filling of said reservoir has been completed to prevent the flow of air through said small opening.

3. A moistening device for use in conjunction with a container of fuel for filling a pyrophoric lighter or similar device having a fuel reservoir containing absorbent material, comprising: a liquid conducting element providing a channel through which fuel may flow from said container, and venting means communicating with said channel and the ambient atmosphere; said venting means including means to prevent the flow of air therethrough until a predetermined pressure differential is reached between the pressure in said container and the atmospheric pressure surrounding said tube.
